UNITED STATES PATENT OFFICE.

WILLIAM J. CROWE, OF ST. CATHARINES, CANADA.

DESIGN FOR A BADGE.

SPECIFICATION forming part of Design No. 31,057, dated June 27, 1899.

Application filed May 12, 1899. Serial No. 716,593. Term of patent 3½ years.

To all whom it may concern:

Be it known that I, WILLIAM J. CROWE, of St. Catharines, in the Province of Ontario and Dominion of Canada, have invented and produced a new and original Design for a Badge, of which the following is a full, clear, and exact description.

The design relates to emblematic badges, particularly as a memento of the Pan-American fair.

Reference is to be had to the accompanying drawing, forming a part of this specification, the figure being a perspective view of a badge embodying my design.

The leading feature of the design consists of a badge having a shield forming the base and an eagle on the obverse of the shield, the eagle holding a pan.

The minor feature of the design is the ring appearing on the reverse of the shield, as shown.

I claim—

The design for a badge, herein shown and described.

WITNESSES:

JAMES N. WALKER;
E. A. LANCASTER.
